PIPE CUTTER

Carl Alfred Thober, Newark, N. J., assignor to
J. Wiss & Sons Co., Newark, N. J., a corpora-
tion of New Jersey

Application November 4, 1952, Serial No. 22,117

Term of patent 14 years

(Cl. D54—13)

To all whom it may concern:

Be it known that I, Carl A. Thober, a citizen of the United States of America and a resident of Newark, county of Essex, and State of New Jersey, have invented a new, original, and ornamental Design for a Pipe Cutter, of which the following is a specification, reference being had to the accompanying drawing forming a part thereof.

Figure 1 is an end elevational view of a pipe cutter embodying my new design, showing the blades in closed position;

Figure 2 is a side elevational view thereof;

Figure 3 is a front elevational view thereof;

Figure 4 is an elevational view of the other side thereof;

Figure 5 is a rear elevational view of the pipe cutter;

Figure 6 is an enlarged end elevational view opposite that shown in Figure 1 with the blades in open position;

Fig. 7 is a front elevational view showing the blades in open position; and

Fig. 8 is a rear elevational view showing the blades in open position.

I claim:

The ornamental design for a pipe cutter, as shown.

CARL ALFRED THOBER.
